CLAIM

The ornamental design for a door buffer assembly, as shown and described.

DESCRIPTION

FIG. 1 is a front view of a first component of a door buffer assembly showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and

FIG. 7 is a front, left and top perspective view thereof.

FIG. 8 is a front view of a second component of the door buffer assembly thereof;

FIG. 9 is a rear view thereof;

FIG. 10 is a left side view thereof;

FIG. 11 is a right side view thereof;

FIG. 12 is a top plan view thereof;

FIG. 13 is a bottom plan view thereof; and

FIG. 14 is a front, left and top perspective view thereof.

FIG. 15 is a perspective view of the door buffer assembly thereof, shown in a separated state; and,

FIG. 16 is a front view of a second component of the door buffer assembly thereof, shown in a combined state.

The broken lines shown in the drawings illustrate portions of the Door Buffer Assembly that form no part of the claimed design.
